UNITED STATES PATENT OFFICE.

MARK THOMAS DENNE, OF LONDON, ENGLAND.

PRESSER-FOOT MECHANISM FOR SHOE-SEWING MACHINES.

SPECIFICATION forming part of Letters Patent No. 737,716, dated September 1, 1903.

Application filed August 9, 1902. Serial No. 119,147. (No model.)

To all whom it may concern:

Be it known that I, MARK THOMAS DENNE, a subject of the King of Great Britain, residing at 22 Finborough road, Fulham, London, 5 England, have invented new and useful Improvements in Presser-Foot Mechanism for Shoe-Sewing Machines, of which the following is a specification.

This invention relates to boot and shoe 10 sewing machines of the type described in the specifications of Letters Patent Nos. 505,034 and 529,064 and to such machines which have an adjustable presser-foot, and has for its object the improvement of the mechanism for locking or preventing the presser-foot from yielding while the needle is passing through the work and the stitch being formed.

To enable the invention to be fully understood, I will describe the same by reference 15 to the accompanying drawings, in which—

Figure 1 is an elevation of the boot and shoe sewing machine shown and described in the specification of patent application, Serial No. 67,471, filed July 8, 1901, and having my 20 improved mechanism for controlling the presser-foot applied thereto. Fig. 2 is a side elevation of the said mechanism detached. Fig. 3 is a plan thereof; and Fig. 4 is a section on the line 4-4, Fig. 3. Fig. 5 represents 25 a top plan view of the locking-pawl and showing a portion of the segment. Fig. 6 is an enlarged partial side elevation of the pawl and segment.

a is the framing of the machine, and *b* the 30 main or cam shaft.

d is the needle, and *f* the awl, both oscillating about a common center *f'*.

g is the race containing the shuttle, which rotates in a plane at right angles to the needle and awl.

h is the table or support for the work, the said support having in it a slot for the passage of the awl *f* from the under side and the needle *d* from the upper side.

h is the presser-foot or channel-guide arranged to turn about the center *f'*, so that it can be adjusted relatively with the work-support *h*, according to the thickness of the work, and its pressure relieved while the work is 45 being fed by the awl.

h is the lever-handle, fulcrumed to the frame at *h* and connected to the presser-foot

through the medium of the lever *h*, link *h*, and arm *h* on the said presser-foot, whereby the latter can be lifted in order to enable the 55 work to be placed in position on the table *h*.

h is a spring one end of which is connected to the lever *h*, while the other end is connected to the frame *a*, the said spring serving to cause the presser-foot *h* to bear with pressure upon the work and hold it firmly.

All of the above parts are of known construction.

I will now describe my improvements.

In carrying out my invention I provide 65 the lever-handle *h* with an extension *i*, having a segment of rack-teeth *i* *i'*, the said extension having its center at the fulcrum *h*.

i is a spring-pawl which by engaging the teeth *i* locks the presser-foot, the said pawl 70 sliding in a recess *i* in a lever *i*, fulcrumed at *i* and *i* in the frame *a* of the machine and in a bracket *i*, respectively. For enabling the pressure of the presser-foot on the work to be relieved while the awl is feeding the 75 work I provide the lever *i* with a roller *i*, held in contact with the periphery of the disk *g* (which in this machine has a cam-groove for operating the awl) by the spring *i*, the said disk having a cam groove or surface *i* 80 in the path of the said roller, so that in the rotation of the said disk *g* when the said cam groove or surface *i* comes opposite the roller the latter will be caused to enter it by the spring *i*, thereby turning the lever *i* on 85 its fulcrum and turning the lever *h* also upon its fulcrum through the medium of the pawl *i* and extension *i* and through the medium of the connections *h* *h* *h* slightly lifting the presser-foot *h*. For unlocking the presser- 90 foot when it is required to place the work on the work-table and to allow of the automatic adjustment of the presser-foot to various thicknesses of stock I arrange that the pawl shall be withdrawn from the part *i* of the lever *h*, and for this purpose I form a cam or raised surface *j* upon the disk *g*, and I fulcrum to the bracket *i* a lever *j*, carrying at one end a roller *j*, designed to be held against the disk *g* in the path of the cam-surface *j* by means of a spring *j*, connected at 95 one end to an extension on the said lever, while the other end is connected to the bracket *i*. The other end of the lever *j* is

provided with a pin j^4 , which extends through a hole j^7 , Fig. 2, in the bracket i^7 and bears against a crank-arm j^5 , fulcrumed to the bracket i^7 , the upper end of the said arm j^5 5 engaging a recess j^0 in the pawl i^2 . The part of the pin j^4 which bears against the arm j^5 is preferably formed eccentric to the main part, (which is screwed into the lever j'), so that it can be adjusted relatively with the 10 said arm by rotating it. By the described arrangement when the cam-surface j comes into contact with the roller j^3 the pin j^4 is caused to press against the arm j^5 and forces back the pawl i^2 out of engagement with the 15 teeth i^3 of the part i of the lever h^0 , so that the latter can be moved to lift the presser-foot h^2 . The pawl i^2 is advantageously formed of a series of bars laid side by side in the recess i^3 , each of the said bars having a recess 20 j^6 at its rear end for the reception of a spring j^8 , one end of which bears against the end of the recess j^6 , while the other end bears against a plate j^9 , fixed to the lever i^4 by a screw j^{10} . In the drawings the pawl is shown as 25 consisting of four bars, as indicated in Fig. 4 by the dotted lines. By constructing the pawl in parts or sections, as described, the points of each part can be more easily ground when removed from the recess i^3 than if the pawl 30 were formed of one piece. The points of the various sections of the pawl can be so disposed one with the other, as shown in an exaggerated manner in Fig. 6, as to give a fine adjustment with a coarse pitch of teeth in 35 the segment-rack. Thus if the pitch of the segment-teeth is sixteen to the inch and there are four pawls the points of which are set one sixty-fourth of an inch apart then the segment can be locked at intervals of one 40 sixty-fourth of an inch, while a strong tooth is used of one-sixteenth of an inch pitch on the segment.

j^{11} is a cam projection similar to the projection j and which I advantageously employ 45 for operating the lever j' to move the pawl i^2 to release the presser-foot just before the awl leaves the work after it has done feeding the same.

Having now particularly described and ascertained the nature of my said invention and in what manner the same is to be performed, I declare that what I claim is—

1. In a sewing-machine, the combination with the needle, awl and shuttle, and a work-supporting table, of a pivoted presser-foot, a spring-operated hand-lever connected thereto and provided with a ratchet-segment, a pivoted locking-frame, a longitudinally-movable pawl carried by said frame and engaging said 55 segment, to lock the presser-foot in operative position, and a cam for rocking said locking- 60 frame, on its pivotal supports to lift said presser-foot while the work is being fed, substantially as described.

2. In a sewing-machine, the combination 65 with the needle, awl and shuttle, and a work-supporting table, of a pivoted presser-foot, a spring-operated hand-lever connected thereto and provided with a ratchet-segment, a pivoted locking-frame, a longitudinally-movable 70 pawl carried by said frame, and engaging said segment, to lock the presser-foot in operative position, a cam for rocking said locking-frame on its pivotal supports to lift said presser-foot while the work is being fed, and mechanism 75 for retracting said pawl longitudinally to disengage said pawl from said segment to release the pawl after the feeding movement, substantially as described.

3. In a sewing-machine, the combination 80 with the needle, awl and shuttle, and a work-supporting table, of a pivoted presser-foot, a spring-operated hand-lever connected thereto and provided with a ratchet-segment, a pivoted locking-frame, a longitudinally-movable 85 pawl carried by said frame and engaging said segment, to lock the presser-foot in operative position, a spring engaging said pawl and forcing it into engagement with said segment, a part connected with said locking-frame 90 provided with a friction-roll, a cam engaging said roll for rocking said frame and lifting said presser-foot while the work is being fed, mechanism for retracting said pawl including an arm provided with a friction-roll and a 95 cam engaging said arm for retracting said pawl longitudinally to release the segment and presser-foot at the conclusion of the feeding movement, substantially as described.

4. In a sewing-machine, the combination 100 with the needle, awl and shuttle, and a work-supporting table, of a pivoted presser-foot, a spring-operated hand-lever connected thereto and provided with a ratchet-segment, a pivoted locking-frame a plurality of longitudinally-movable 105 pawls carried by said frame and having their points out of line with each other, an independent spring for each pawl for holding them in engagement with the segment, an arm connected with said locking-frame, and provided with a friction-roll, a cam engaging said roll to rock said frame and lift said presser-foot, a lever engaging all of 110 said pawls, mechanism for operating said lever including an arm provided with a friction-roll, and a cam engaging said roll for withdrawing all of said pawls simultaneously, 115 substantially as described.

MARK THOMAS DENNE.
